WALL-MOUNTED HEADBOARD FOR A BED

Kathleen Elliott, 220 E. 26th St.,
New York, N.Y. 10010

Filed Dec. 26, 1968, Ser. No. 15,119

Term of patent 14 years

Int. Cl. D6—01

U.S. Cl. D5—4

Fig. 3

FIG. 1 is a front view of a wall-mounted headboard for a bed showing my new design;

FIG. 2 is a top view thereof; and

FIG. 3 is a cross-sectional view taken through line 3—3 of FIG. 1.

The back of the headboard is plain and unornamented. I claim:

The ornamental design for a wall-mounted headboard for a bed, substantially as shown and described.
